COMPUTING AND PRINTING MACHINE

Oscar J. Sundstrand, Rockford, Ill., assignor, by
mesne assignments, to Underwood Elliott Fisher
Company, New York, N. Y., a corporation of
Delaware

Application June 26, 1926, Serial No. 118,628

54 Claims. (Cl. 235—60)

This invention has particular reference to machines which are adapted for use in making entries upon ledger sheets and in preparing statements for customers. In such work the statement sheet or the ledger sheet, or both, are supported upon a carriage which is arranged for lateral movement to carry the paper horizontally past the printing mechanism, means being provided to arrest the carriage at each columnar position required by the statement or ledger sheet.

In machines of this class it is desirable that means be provided for automatically controlling various mechanisms of the computing machine so that the proper operation shall occur at each 15 columnar position, as, for example, the printing of a date, or the printing and nonaddition of a folio, or addition, or subtraction, or the taking of a spacing stroke of the handle, or the printing of the total. A particular object of the present invention is to provide improved construction for controlling various computing machine mechanisms, said control means being of a compact nature capable of being readily incorporated in a computing machine without reorganization 20 of the latter.

In prior machines of the class referred to, the stops carried by the carriage for coaction with the carriage escapement and the devices that control the various mechanisms of the machine 30 have been more or less complicated and thus liable to misadjustment by the operator. One of the objects of this invention is to provide simple and inexpensive stop means on the carriage which shall obviate any possibility of misadjustment. 35 This feature of the invention is herein shown as embodied in a plate having permanently fixed thereto stop pins capable of effecting the operations required by the particular form of statement or ledger sheet to be used, and thus requiring no attention or care on the part of the operator. The stop plate is made readily attachable to and detachable from the carriage so that when 40 a different printed form is to be used the operator may conveniently substitute a stop plate corresponding to the character of the work in hand.

Another object is to provide simple and effective means for controlling the printing of dates, for effecting repeated printing of a desired amount, for effecting printing of the total with- 50 cut clearing of the machine, for effecting non-addition, for effecting printing of the total accompanied by clearing of the machine, and for controlling platen feed or line spacing.

Another object of the invention is to provide 55 means for introducing the additional unit re-

quired in order that the correct total shall be printed when the total is an over-draft or credit balance. This feature of the invention is useful in machines which are not provided with a cross-tabulating carriage such as heretofore referred to. 5

A further object is to provide means which is sensitive to the positive or negative character of the total contained in the machine for automatically conditioning the machine to print the correct total, thus obviating the necessity of means 10 for warning the operator when the machine contains a negative total and means for manually conditioning the machine for the printing of such a total.

In the accompanying drawings: 15

Figure 1 is a fragmental longitudinal vertical sectional view of one form of machine embodying the features of my invention, the view being taken from the right-hand side of the machine.

Fig. 1a is a fragmental view of the carriage 20 escapement mechanism.

Fig. 1b is a fragmental view of the tabulating mechanism, i. e., the mechanism for moving the carriage from one position to the next without operating the handle. 25

Fig. 2 is a view generally similar to Fig. 1.

Fig. 3 also is a view generally similar to Figs. 1 and 2, but showing the carriage in its extreme left-hand position, the handle having started on its return stroke, with the parts in position to 30 print a grand total.

Fig. 3a is a detail view of the cam 148.

Fig. 4 shows the handle in its extreme forward position in the taking of a spacing stroke for the purpose of placing the totalizer in mesh with 35 the front or subtracting racks, there being a credit balance in the machine.

Fig. 5 shows a fragmental view of the machine in initial position, there being a debit or positive balance in the machine. 40

Fig. 5a is a detail view of the right-hand lever 139.

Fig. 6 is a view showing how the computing mechanism is set for subtraction by the conjoint action of the paper carriage and the operating 45 handle.

Fig. 7 is a fragmental plan section of a portion of the means for controlling the computing mechanism in the manner just referred to.

Fig. 8 is a fragmentary illustration of the 50 machine, the handle being in the initial position, there being a credit balance in the totalizer and an amount having been set up on the keyboard.

Fig. 9 is a fragmentary front view. 55

Fig. 10 is a fragmental view from the left-hand side of the machine with the parts in the initial position.

Fig. 11 is a fragmental plan view illustrating the computing mechanism (the racks being omitted), the means for setting said mechanism for subtraction, and the means for controlling said setting means in accordance with the character (i. e., positive or negative) of the total in 10 the totalizer.

Fig. 12 is a fragmental right-hand view showing more particularly the non-add mechanism.

Fig. 13 is a fragmental view of the printing and computing mechanism.

Fig. 14 is a generally similar view, but showing the mechanism for introducing the fugitive unit, said unit having just been introduced at the subtracting side of the machine.

Fig. 14a is a perspective detail view of certain parts comprised in the means for controlling the means for operating the computing mechanism in accordance with the character of the total.

Fig. 15 is a view similar to Fig. 14, the fugitive unit having just been introduced at the adding 25 side of the machine.

Fig. 15a is a fragmental perspective view of the means for introducing the fugitive unit.

Fig. 16 is a fragmental rear view.

Fig. 17 is a fragmental view from the left-hand 30 side of the machine, showing the means for actuating the line-space mechanism.

Fig. 18 is a fragmental view from the left-hand side showing the means for controlling the date and symbol type bars.

Fig. 18a is a detail view of a slide comprised 35 in the means for controlling line-spacing and non-printing.

Fig. 19 illustrates the keyboard.

Fig. 20 is a fragmental view of the means for 40 turning the right-hand platen section to effect line-spacing.

Fig. 21 is a fragmental view looking from the front, illustrating the means for controlling the computing mechanism.

Figs. 22 to 29, inclusive, are detail views of 45 devices by which the carriage is controlled and by which the carriage controls various adding machine mechanisms.

Fig. 30 is a view more or less diagrammatic 50 showing the two platen sections, the statement supported by one platen section, the ledger sheet carried by the other platen section, and the detachable stop plate carried by the platen carriage.

Fig. 31 is a detail view of the rock shaft to 55 which the stop plate is attached.

Figs. 32 and 33 are sectional views of the stop plate and adjacent parts.

Fig. 34 is a plan view illustrating the parts 60 shown in Figs. 18 and 22 to 29.

The invention is herein shown as embodied in a machine of the general character disclosed in the Sundstrand Patents Nos. 1,198,487, 1,481,487 and 1,583,102, although it will be understood that 65 the invention is not limited to machines of the Sundstrand type. Reference may be made to the above mentioned patents for an understanding of features not fully illustrated or described herein. Certain other features which are herein 70 disclosed in part are more fully described and illustrated in my application Ser. No. 670,665 filed October 25, 1923 (now Patent No. 1,965,611, granted July 10, 1934).

The paper on which records are to be made is 5 supported upon a carriage 1 (Fig. 1) which is

mounted for lateral movement on top of the rear portion of the supporting framework F of the machine. On the carriage 1 is a cylindrical platen 2 (Fig. 30). Herein the platen is indicated as consisting of two sections 2^a and 2^b axially aligned and capable of independent manual rotation, but arranged to be simultaneously rotated by mechanical means common in the art.

The printing is effected by means of vertically reciprocatory type bars 3 (Fig. 13) which are 10 raised and lowered by means including arms 13 (Figs. 16 and 18). Said arms are yieldingly connected through coiled contractile springs 14 to a rod 15. The latter is carried by two side members 16 the upper ends of which are pivoted at 15 16^a to three-arm levers 19 that are pivoted on the axis 19^a (Figs. 3 and 17). Links 23 (Fig. 1) are pivoted to the lower ends of the levers 19 at 23^a the forward ends of said links being pivoted to two crank arms 24 and 25 (Figs. 1 and 10) 20 fixed to opposite ends of a rock shaft 26. The shaft 26 is arranged to be rocked by means of a handle 27 mounted to swing on the axis 28. The handle 27 is connected to the arm 24 by means which may be of any preferred character as, for 25 example, that shown in the Sundstrand Patent No. 1,611,390. It will, of course, be understood that an electric motor may be used to rock the shaft 26, if desired.

When the operator pulls the handle 27 forward, the arms 24 and 25 swing upwardly, thereby drawing the lower ends of the levers 19 forwardly and moving the side members 16 and the rod 15 downwardly. The movement of the rod 15 is 30 yieldingly transmitted through the springs 14 and the arms 13 to such of the type bars 3 as are at liberty to rise. The means for restoring the type bars to their normal down position may be of any well known or preferred construction as, for example, that shown in my application Serial No. 40 670,665.

The means for limiting the ascent of the type bars which print amounts and folio numbers may be like that disclosed in Patent No. 1,198,487. The extent of rising movement of the type bars 45 that print dates and explanatory symbols may be determined by means such as that described in Patent No. 1,481,487.

The keyboard is shown in Fig. 19. 49 are the 50 numeral keys by means of which numbers are set up in the group of stops (not shown). The means for eliminating a number from the stops is fully described in Patent No. 1,198,487 and comprises a bar 72 (Fig. 10) provided with a roller stud 73. A bar 74 guided for movement 55 alongside the bar 72 is arranged to be reciprocated in the movement of the handle 27. A spring 71 normally holds the bar 74 up so that its forward end will strike the stud 73 and thus push the bar 72 forward, thereby eliminating the 60 number set up in the stops.

When a number is to be printed or accumulated more than once, the bar 74 is held down so as not to engage the stud 73. The repeat or multiplying key 84 (Fig. 19) provided for this 65 purpose is described in Patent No. 1,198,487.

The back-spacer key 86 may be connected and arranged in any preferred manner or as shown in the Sundstrand patents hereinbefore mentioned. The non-print key 120 may be connected 70 to the hammer-release mechanism as in the Sundstrand Patent No. 1,455,555, or in any other desired way.

For a full disclosure of certain features of the computing mechanism, reference may be made 75

to my application Ser. No. 670,665 filed October 25, 1923. Said mechanism comprises a series of pinions 125 (Fig. 13) rotatably mounted upon a transverse shaft 126 which is supported for movement longitudinally of the machine, i. e., backward and forward. The set of pinions 125 is located between two sets of racks 129 and 130 which constitute differential mechanism. Both sets of racks are connected to the type bars that print amounts and folio numbers, and the set of pinions is arranged to be moved into mesh with either set of racks.

Addition is accomplished by means of the set of racks 130. When an amount is to be added 15 the set of pinions is moved forward into neutral position between the two sets of racks before the type bars are raised, and the set of pinions is moved rearwardly into mesh with the racks 130 just before the type bars are moved downwardly. Addition therefore occurs in the down stroke of the racks 130.

Subtraction is accomplished by rotating the pinions 125 in the reverse direction by means of the racks 129, subtraction occurring in the down- 20 stroke of said racks.

The upper end of each rack is attached to a rearwardly extending portion 131 of one of the type bars by means of a headed stud 132 extending through a vertically elongated opening 133 25 in the rack. A contractile spring 134 attached at its upper end to the rack at 134^a and at its lower end to a downwardly-extending portion 135 of the type bar tends to move the rack downwardly one tooth space with relation to the type bar. The backs of the racks slide in grooves in stationary guide bars 136.

The pinions 125 are moved into and out of mesh with the racks 129 and 130 by means of two links 137 (Fig. 5) one at each side of the 30 machine, the forward ends of which have bearings to receive the ends of the shaft 126. The rear ends of the links 137 are pivoted at 138 to the lower arms of two levers 139 (Figs. 5 and 5a) which are rigidly secured to a shaft 140 35 journaled in the machine frame. When the levers 139 are in the position shown in Fig. 5, the pinions are in neutral position. When the levers 139 swing clockwise out of such position, the pinions move into mesh with the subtracting racks 129; and when the levers 139 swing counterclockwise out of such position the pinions move into mesh with the adding racks 130. The means for swinging the levers 139 to move the pinions into and out of mesh with the racks 50 40 comprises a link 141 (Fig. 6) the forward end of which is supported by a lever 141^a pivoted at 141^b. The rear end of the link is provided with notches 142 and 143 to receive pins 144 and 145 (Fig. 5a), respectively, on opposite ends of the 55 right-hand lever 139. Rearwardly of the notches 142 and 143 are lugs 146 and 147, respectively, which serve to prevent disengagement of the lever 139 from the link 141. Forwardly of the notches 142 and 143 are curved surfaces adapted 60 to slide in contact with the pins 144 and 145. The link 141 is moved forward and back by means of an oscillatory cam plate 148 (Fig. 3a) having a cam slot 149 therein, said cam plate being pivoted at 150 (Fig. 2). On the forward 65 end of the link 141 is a roller that lies in the slot 149.

The means for oscillating the cam 148 comprises a reversible pawl 152 (Figs. 2 and 6) which is pivoted at 153 upon a plate 154 rigidly secured 70 to the arm 24. One side of the pawl is adapted

to engage a pin 156 (Fig. 2) set in the cam plate 148 at one side of its axis 150, the other side of the pawl being adapted to engage a pin 157 (Fig. 3) fixed in the cam 148 at the opposite side of its axis.

When a number is to be added or subtracted, the pawl 152 is permitted to engage the pins 156 and 157 so as to swing the cam 148 to effect movement of the pinions into and out of mesh with the racks. 10

When a total (whether subtotal or final total) is to be printed the pawl 152 is not permitted to engage the pin 156; consequently, the cam 148 is not moved during the forward stroke of the handle 27, and the pinions remain in mesh with the racks 15 during the rising of the latter, thereby effecting the positioning of the type bars for the printing of the total.

The means for controlling engagement of the pawl 152 with the pin 156 includes an arm 159 20 (Fig. 3) pivoted at 160 in the machine frame, the upper end of said arm being adapted to hold the pawl 152 out of position to engage said pin. As explained in application Serial No. 670,665, after a spacing cycle or a total-taking cycle and 25 until a number has been set up in the stop mechanism, the arm 159 is in its forward position. As soon as a digit is set up in the stop mechanism, the arm 159 swings rearwardly away from the pawl 152 and leaves said pawl in position to engage the pin 156 when the handle 27 is pulled. When a debit or credit total is to be printed, the pawl 152 is held out of engagement with the pin 156; consequently the cam 148 is not moved during the forward stroke of the handle 27 and 30 the totalizer remains in mesh with the racks during the rise of the latter, thereby effecting the positioning of the type bars for the printing of the total.

When it is not desired to clear the machine after 40 printing a debit total, the totalizer is allowed to remain in mesh with the racks 130 during the downward movement thereof. When, however, the operator wishes to clear the machine of a debit total, the pinions are withdrawn from the racks 45 130 before the latter descend. The means for swinging the cam 148 to effect such movement of the pinions comprises a lever 164 (Fig. 2) pivoted on the shaft 26 and having a cam slot 165 in which lies a roller 166 on the cam 148. The lever 164 has an arm 167 (Fig. 3) which is arranged to be engaged by a pin (not shown) on the arm 24. The means for swinging the lever 164 forward to disengage the pinions from the racks 130 is controlled by a clear or grand total 50 key 169 (Fig. 3) having a stem 170. On the stem 170 is a stud 171 that underlies the forward end of a lever 172. The lever 172 has an elongated opening 173 through which a pivot rod 174 extends, the lever 172 thus being movable longitudinally to a slight extent. A contractile spring 175 tends to slide the lever 172 rearwardly. 176 is a contractile spring stretched between a pin on the stem 170 and the front end of the lever 172 and tending to hold the pin 171 and the lever 172 55 in contact with each other. During the printing of an amount and during the enforced blank or spacing stroke of the handle prior to the taking of a total, the lever 172 is held against movement by the spring 176 by means fully described in application Ser. No. 670,665. After the blank stroke has been taken, if the total key 169 be depressed, the rear arm of the lever 172 is permitted 60 to rise under the influence of the spring 176 during the next forward stroke of the handle, 70 75

so as to place a shoulder 193 on the lever 172 behind a pin 194 on the lever 164. Very shortly after the handle 21 has commenced its return stroke, means fully described in said application 5 Serial No. 670,665 pushes the lever 172 forward, thus pushing the lever 164 forward, thereby swinging the cam 148 upward and thus pulling the link 141 forward. Said link being in engagement with the pins 145 on the lever 139, the pinions are 10 moved forward out of mesh with the racks 130 and thus left standing at zero.

Referring now to the transfer mechanism (best shown in Fig. 13): There is a set of transfer devices for the racks 130 to carry amounts from one 15 numerical order to the next higher order in operations involving addition, and a set of transfer devices for the racks 129 to carry amounts from one numerical order to the next higher order in operations involving subtraction. The extent of 20 downward movement of the tens and higher racks is limited (except in the transfer operation) by contact of lugs 203 on the racks with stop lugs 204. When an amount is to be transferred from one order to the next higher order, the stop lug 25 204 for the rack belonging to such higher order is withdrawn, thereby allowing that rack to descend under the action of its spring 134 until its lug 203 stops against the bar 136 as indicated in the right-hand portion of Fig. 15. The extent 30 of such further descent of the rack is just sufficient to turn the pinion for that rack through the distance of one tooth. Each stop lug 204 is formed on an arm or pawl 205 which is pivoted on a rod 206 in the framework of the machine. 35 To the lower end of each pawl 205 is pivoted a dog 207 having a tooth 208 adapted to engage the edge of the adjacent bar 136. A contractile spring 209 normally holds the tooth 208 in engagement with the bar 136, the lug 204 being then 40 in position to support the corresponding rack.

The means for disengaging the tooth 208 from the bar 136 consists of two diametrically opposite lugs 210 fixed to one side of each pinion. (Two lugs 210 are provided because each pinion has 45 twenty teeth.) When the amount registered by a pinion reaches nine, continued rotation of the pinion as its rack descends brings one of the lugs 210 against the end of the dog 207 associated with the next higher rack, thereby depressing the 50 dog until the tooth 208 is clear of the bar 136, whereupon the spring 209 (assisted by the downward pressure of said next higher rack) pulls the dog and the pawl 205 away from the last mentioned rack, the latter then moving down one 55 tooth space under the influence of its spring 134, being stopped by the bar 136.

It may be here stated that when any pinion stands at zero, one of the lugs 210 on said pinion lies directly beneath one of the dogs 207 associated with the set of racks 130 if the amount accumulated is a debit or positive amount, or directly beneath one of the dogs 207 associated with the group of racks 129 if the amount accumulated be a credit or negative amount. Therefore, when a total is to be printed, those racks which mesh with the pinions standing at zero cannot rise, the remaining racks rising until the rotation of their pinions brings the lugs 210 thereon into contact with the respective dogs 207. The 70 type bars 3 are then in position to print the total amount accumulated on the pinions.

If a debit or positive amount has been accumulated in the machine, and one or more amounts are subtracted so as to leave a credit or negative 75 total in the machine, the true credit or nega-

tive total cannot be printed until the credit or negative total in the machine has been increased by one unit. Similarly, if a credit or negative total be converted into a debit or positive total by the addition of amounts, the correct total cannot be printed without first adding a unit to the total in the machine. In other words, in order that the correct total shall be printed it is necessary to introduce a unit into the totalizer whenever the totalizer has "passed through zero." 10 In order to effect this result automatically, I have provided the means to be now described.

The units rack 129 is arranged to be supported in normal position by means of a pawl 218^a (Fig. 14) which is pivoted upon the rod 206 and is 15 arranged to support the lug 203 on said units rack. When the "fugitive 1" is to be introduced into the totalizer, the pawl 218^a is moved out of engagement with the lug 203 of the units rack, whereupon the spring 134 for said rack moves 20 the rack down one tooth space and thus turns the units pinion the same distance. The means for thus moving the pawl 218^a at the time the totalizer passes through zero comprises two diametrically opposite lugs 218^b (Fig. 11) on the 25 pinion of highest order, said lugs being arranged to engage a dog 218^c (Fig. 15a) which may be and preferably is identical in form with the dogs 207. The dog 218^c is pivotally supported upon a member 218^d which is pivoted on the rod 206. 30 For simplicity of manufacture, the member 218^d has a lug like that of the pawl 218^a, although it has no rack-supporting function. Each of the members 218^a and 218^d are provided with upwardly extending arms 218^e which are rigidly 35 connected together by means of a cross bar or plate 218^f.

Let it be assumed that the amount "3" has been accumulated or added by operation of the adding racks 130. The units pinion will therefore 40 stand with one of its lugs 210 three spaces below the zero position on the adding side of the machine, the corresponding lugs 210 of the other pinions lying directly beneath the dogs 207 at the same side of the machine. The diametrically 45 opposite lugs 210 are above the horizontal plane of the dogs 207 at the subtracting side of the machine. Assuming that 5 is to be subtracted, the pinions are first moved out of mesh with the racks 130, and after the units rack 129 has been 50 raised to the position for registering "5", the pinions are moved into mesh with the racks 129, whereupon the units rack 129 descends, thus turning the units pinion five tooth spaces. In the course of such turning movement, one of the 55 lugs 210 on the units wheel is carried into engagement with the end of the dog 207 associated with the tens rack 129, thereby disengaging said dog from the bar 136 and thus allowing said tens rack to descend one tooth space. Said tens 60 rack being in mesh with the tens pinion, the latter was caused to turn through one tooth space, whereby the lug 210 on said tens wheel tripped the dog 207 for the hundreds rack, and so on from pinion to pinion. An impulse was thus 65 transmitted from the units pinion to the pinion of highest order so as to place one of the lugs 210 on all the pinions except the units pinion directly below the normal horizontal plane of the dogs 207 at the subtracting side of the machine. The rotation thus imparted to the wheel of 70 highest order served to disengage the dog 218^c from the bar 136, whereupon the corresponding spring 209 moved said pawl and the member 218^d forward, the forward swing of the member 218^d 75

being transmitted through the arms 218^e and the plate 218^f to the pawl 218^a, whereby the units rack 129 was allowed to descend an additional tooth space, thus introducing the "fugitive 1".

5 The means for introducing the "fugitive 1" at the adding side of the machine is like that just described, and similar reference numerals have been applied to the parts in the drawings.

For an understanding of the means for restoring the transfer pawls 205, the transfer dogs 207, the dog 218^c, the pawl 218^a and the member 218^d, reference may be made to application Serial No. 670,665.

No. 2,070,301

When the machine is clear, the link 141 is in engagement with the pin 145, the pinions being then in mesh with the racks 130. Reciprocation of the link 141 will therefore shift the pinions into and out of mesh with those racks. When an amount is to be subtracted, the link 141 is shifted 15 into engagement with the pin 144. The means for shifting the link 141 comprises a lever 219 (Fig. 1) pivoted at 220 in the machine frame and having a forked rear end which engages a pin 221 on the link 141. The lever 219 has a 20 downwardly extending arm 222 to which is attached a contractile spring 223 that serves to raise the lever 219 and hence the link 141. The spring 223 is controlled by means including a subtraction key 224 having a vertically movable 25 stem 225. A contractile spring 226 normally holds the subtraction key elevated. On the stem 225 is a pin 227 that overlies a forwardly extending arm 228 pivoted at 229. Rigid with the arm 228 is a downwardly extending arm 230. 30 A contractile spring 231 connected to the arm 230 tends to draw said arm forward, said spring, assisted by gravity, tending to place the link 141 in position to condition the registering mechanism for a positive operation. The computing 35 mechanism is locked in position to subtract by means of a finger 232 fixed to one end of a rock shaft 233 and adapted to overlie the arm 228. To the other end of the shaft 233 is fixed a finger 234 (Figs. 8 and 9) to which is attached a spring 40 45 235 tending to draw the finger 234 rearwardly. The lower end of the finger 234 normally bears against a roller 236 carried by the slide bar 72. When an amount is set up by depression of the keys 49, the bar 72 moves rearwardly (to the right in Fig. 8) thus allowing the spring 235 to swing the finger 232 rearwardly. When the arm 228 is swung downwardly it slips past the finger 232, whereupon said finger swings back over said arm, as shown in Fig. 6.

To the arm 230 is pivoted a link 240 which has a lost-motion connection with the arm 222 consisting of a headed stud 241 on the arm 222 extending through an elongated hole 242 in the link (Fig. 1). The spring 223 is anchored to the link 240. When the machine is clear, and also when there is a debit balance in the machine, the link 141 is in engagement with the pin 145. When an amount is to be subtracted, the link 240 is moved rearwardly, thus moving the rear end 65 wall of the opening 242 away from the stud 241. When the handle is pulled, the link 141 is drawn forward, as before explained, to withdraw the pinions from the racks 130 before the racks rise. The forward movement of the link 141 causes 70 the lever 139 to rock, as a result of which the pin 144 is brought into register with the notch 142. Thereupon the spring 223 lifts the lever 219, thus placing the notch 142 in engagement with the pin 144. In the return stroke of the handle, 75 the link 141 is pushed rearwardly, thereby rock-

ing the lever 139 in the direction to place the pinions in mesh with the racks 129 before the latter start down. In the descent of the racks, the amount is subtracted. At the end of the return stroke of the handle, the finger 232 is withdrawn from the arm 228. In the next forward stroke of the handle, the link 141 is drawn forward to place the pinions in central position before the racks ascend.

In work of the character shown in Fig. 30, the next record to be made after a credit entry is the folio, which, of course, is not to be added. Non-addition is effected by means acting to prevent the pawl 152 (Fig. 3) from engaging the pin 157 so that the pinions 125 shall remain in central position during the down stroke of the racks. The non-add mechanism is fully described in application Ser. No. 670,665 and hence it is sufficient to say that it comprises a slide 255 (Fig. 6) arranged, when in its rear position, to be engaged by a pin 259 on the pawl 152 and thus prevent the pawl 152 from engaging the pin 157 in the backward movement of said pawl. A spring 258 tends to draw the slide rearwardly. The means for releasing the slide to the action of the spring 258 comprises a non-add key 264 (Fig. 19).

The machine is preferably arranged to print totals in a color contrasting with the remainder of the work, as, for example, totals in red, and the rest of the work in blue. The ribbon shift mechanism may be of any preferred character.

The paper carriage 1 is mounted on top of the framework of the machine for lateral movement. Any well known or preferred means may be employed to move the carriage toward the left, a portion of the carriage-moving spring 1000 being shown in Fig. 16. If desired, motive means may be used to return the carriage to initial position at the right of the machine, or the carriage may be drawn to the right by the operator, as in the present instance.

The carriage 1 is arranged to control various mechanisms, as for example, the repeat mechanism, the date and symbol printing mechanism, the non-add mechanism, the grand total taking or clearing mechanism, the non-print mechanism, the mechanism that sets the computing mechanism to perform subtraction, and the line-space or paper feed mechanism. The controlling mechanism comprises a compact group of slides, each connected to one of the adding machine mechanisms to be controlled, said group of slides being located in the path of stop pins attached to the paper carriage 1.

Referring first to the means for automatically controlling the printing of dates and symbols: The three type bars farthest to the left are employed to print dates and symbols, as indicated in Fig. 19. The stops which control these type bars are set by sliding one or more of the buttons 511 to appropriate positions as described in Patent No. 1,481,487. This is done at the beginning of the operation of posting to an account. In order that the date or symbol shall be printed only at the desired time or times during the travel of the carriage 1, I provide the following described means: The arms 13 (Figs. 16 and 18) which raise and lower the date and symbol type bars have shoulders 1001 arranged to be engaged by lugs 1002 (Fig. 34) on a bar 1003 mounted to slide transversely of the machine. A spring 1004 normally holds a shoulder 1005 (Fig. 16) on the bar 1003 against an abutment 1006, in which position of the bar the lugs 1002 are directly be-

hind the shoulders 1001 on the arms 13. The means for moving the bar 1003 to place the lugs 1002 out of register with the shoulders 1001 comprises a slide 1007 (Fig. 28) arranged to bear 5 against one end of the bar 1003 and having a lug 1008 arranged to be engaged by one or more stop pins 1009 (Fig. 30) on the lower side of an elongated stop plate 1010 attached to the carriage 1. The forward edge of the stop plate 1010 is secured 10 to a rock shaft 1011 (Figs. 1 and 31) mounted in the carriage 1, operating levers 1012 and 1013 (Figs. 1 and 10) being fixed to the ends of said shaft. A spring 1014 (Fig. 32) anchored to a pin 1015 on the carriage is connected to an arm 15 1016 fixed to the rock shaft 1011, and normally holds the rear edge of the stop plate against a guide roller 1016a on the frame that contains the group of slides hereinbefore alluded to. A lug 1017 on said arm serves to limit upward movement of the stop plate by stopping against the pin 1015. The stop plate may be, and preferably is, detachably connected to the rock shaft 1011. Herein said shaft is shown as having a flat upper side against which the plate may lie, there being 20 a cylindrical pivot pin 1018 (Fig. 31), three headed pins 1019 and a short cylindrical locking pin 1020 on the shaft to enter a hole 1021, three notches 1022 and an opening 1023, respectively, in the stop plate. To connect the stop plate to the shaft 1011, the plate is fitted onto the pivot 25 1018 and then swung toward the shaft, the edge having the notches 1022 therein being pushed under the headed pins 1019, and the plate being slipped onto the locking pin 1020. The headed pins 1019 are acted upon by expansive springs 1024 (Fig. 33) which serve to hold the stop plate down against the rock shaft.

When in the leftward travel of the paper carriage one of the stop pins 1009 on the stop plate 1010 strikes the lug 1008, the slide 1007 and the bar 1003 are moved leftward until said slide stops against the abutment 1006, thereby moving the lugs 1002 out of the way of the shoulders 1001, so that when the handle 27 is pulled one or more 40 of the date and symbol type bars 3 may rise to the extent determined by the operation of the buttons 511. One or more stop pins 1009 may be provided on the stop plates, depending upon the nature of the work, all of said pins being located 45 in a line parallel with the direction of travel of the carriage. Upon the return movement of the carriage, the stop pin or pins 1009 slide over the beveled side of the lug 1008, the stop plate tilting to allow the pins to pass said lug.

50 The means for automatically controlling the repeat mechanism comprises a rod 1025 (Fig. 16) mounted to slide transversely of the machine into and out of position to depress the bar 74 (Fig. 10) so that the latter shall not engage the stud 60 73. The outer end of the rod 1025 is connected to one end of a lever 1026 which is pivoted at 65 1027, the other end of said lever being connected to a slide 1028. The slide 1028 is guided at the rear end of the machine for transverse movement. One end of the slide 1028 is connected to a slide 1029 (Fig. 29) which is similar to the slide 1007 and arranged adjacent thereto. On 70 the slide 1029 is a lug 1029a adapted to be engaged by one or more stop pins 1030 on the stop plate 1010. A contractile spring 1031 (Fig. 16) connected to the slide 1028 normally holds the pin 1025 out of the path of movement of the bar 74, and holds the slide 1029 away from the abutment 1006.

75 The means for automatically controlling the

non-add mechanism comprises a member 1032 (Fig. 12) which is pivoted in the machine frame at 1033. When the member 1032 is in the position shown in Fig. 12, a surface 1034 on said member is in position to engage the pin 259 on 5 the pawl 152 and thus depress said pawl so that it cannot engage the pin 157 (Fig. 3) on the cam 148, whereby the pinions 125 are left in central position during the down-stroke of the racks. The means for operating the member 1032 10 comprises a link 1035 pivoted at its forward end to said member at 1035a and slidably supported at its rear end in a slot 1036 (Fig. 16) in a lever 1037. A contractile spring 1038 normally holds the member 1032 against a stationary portion 1039, and thus holds the surface 1034 up out of the path of the pin 259. On the right hand lever 19 is a pin 1040 adapted to engage a lug 1041 on the link 1035 and thus push the link forward to place the surface 1034 in the path 20 of the pin 259. The lower end of the lever 1037 is pivoted to the bed of the machine at 1042. In its upper portion is an elongated opening 1043 through which extends a stop screw 1044 (Fig. 24). The spring 1038 is anchored at a 25 point to the right of the link and consequently normally holds the link 1035 and the lever 1037 over toward the right to the extent determined by contact of the end wall of the opening 1043 with the screw 1044. When in such position the lug 1041 is out of the path of the pin 1040. The upper end of the lever 1037 is connected to a slide 1045 (Fig. 24) having a lug 1046 adapted to be engaged by one or more stop pins 1048 on the stop plate 1010. The spring 1038 30 normally holds the slide 1045 away from the abutment 1006.

The means for automatically controlling the grand total-taking mechanism includes some of the parts just described, namely, the slide 1045, 40 the lever 1037, the pin 1040, the link 1035, and the spring 1038. Referring to Figs. 2 and 3, a lever 1049 is pivoted at 1050, its free end overlying the pin 171 on the stem of the grand total or clear key 169. Said lever is connected to the member 1032 at 1035a and hence is arranged to be swung by means of the spring 1038 and the pin 1040. When the key 169 is depressed by the lever 1049, the grand total mechanism is operated as hereinbefore described.

Normally a total is automatically printed upon the stroke of the handle 27 next following a blank stroke, as explained in Patent No. 1,583,102. In order to prevent a total from being printed except when called for by the character of the bookkeeping form being used, I provide the means to be now described.

An arm 1051 (Fig. 2) rigidly secured to the arm 159 extends rearwardly of the pivot 160. The rear end of the arm 1051 normally lies below a stop 1052 which is herein shown as fixed to the slide 1028. The stop 1052 is therefore under the control of the carriage 1. When a stop pin 1030 on the stop plate 1010 is not pressing against the lug 1029a (Fig. 29), the spring 1031 holds the stop 1052 in the path of upward movement of the arm 1051 and thus prevents the arm 1051 from swinging downwardly into position to depress the dog 152, thereby preventing the taking of a total. When, however, 70 a stop pin 1030 bears against the lug 1029a, the stop 1052 is moved leftward out of the path of the arm 1051; consequently a total will be printed upon the second stroke of the handle, as described in Patent No. 1,583,102.

The means for automatically setting the computing mechanism to perform a negative operation, such as the subtraction of an item or the taking of a negative total comprises a member 5 1057 (Fig. 21) in the nature of a lever pivoted at 1058 and 1059 in the right hand portion of the machine frame. Said lever has a lower arm 1060 adapted to engage a lug 1061 on the link 240. In order that the extent of movement of the arm 1060 need not correspond precisely to the extent of movement of the link 240, the end of 10 said arm which engages the lug 1061 is made capable of yielding. As shown in Fig. 7 the arm 1060 comprises a section 1062 which is pivoted 15 at 1063, a stop lug 1064 on said section being normally held against the edge of the arm 1060 by a contractile spring 1065. The lever 19 and hence the lever 1057 begin moving as soon as the handle 27 starts forward, hence the rearward movement of the link 240 begins promptly with the beginning of the cycle. By reason of the yielding construction of the arm 1062 the rearward movement of the link 240 is permitted to cease well before the end of the forward stroke, 20 thus insuring time for the latch finger 232 to engage the arm 228.

The member 1057 also comprises an upper arm 1066 (Fig. 21) having a forked end which engages a pin 1067 on the adjacent lever 19. 30 It will be seen that the arm 1060 will be oscillated every time the handle 27 is operated. In order that said arm shall engage the lug 1061 only when the computing mechanism is to be set for a negative operation, the member 1057 35 is mounted for vertical movement, gravity normally holding said member in its lower position (wherein the section 1062 is below the horizontal plane of the lug 1061), and means being provided for raising said member 1057 to place the 40 section 1062 in the horizontal plane of the lug 1061. Two such raising means are provided, one for actuation by the carriage when subtraction is to be automatically performed in a predetermined columnar position, and the other for 45 actuation by a spring hereinafter mentioned when a negative total is to be taken. The carriage-controlled means for raising the lever 1057 comprises a lever 1068 (Fig. 21) pivoted, for convenience, on the screw 1044, the lower arm 50 of said lever extending under the arm 1066. The upper arm of the lever 1068 engages a slide 1069 having a lug 1070 arranged to be engaged by one or more stop pins 1071 on the stop plate 1010. The weight of the lower arm of the lever 55 1068 normally holds the slide 1069 away from the abutment 1006. When the carriage 1 moves the slide 1069 against the abutment 1006 the lower arm of the lever 1068 lifts the arm 1066, and thus lifts the arm-section 1062 into the 60 horizontal plane of the lug 1061, so that when the handle 27 is pulled, the computing mechanism is set to perform subtraction during the ensuing return stroke of the handle.

At the conclusion of an adding cycle the pinions are in mesh with the adding racks 130, whether the total be positive or negative. At the end of a subtracting cycle, the pinions stand in mesh with the subtraction racks 129, whether the total be positive or negative. If an adding 65 cycle follows a subtraction cycle, the pinions automatically move into mesh with the adding racks 130 through the action of the spring 231 and the weight of the parts 141 and 219. If a blank or spacing cycle follows an adding cycle, 70 the pinions are in mesh with the adding racks

at the conclusion of the blank cycle. If a blank cycle follows a subtraction cycle, the spring 231 tends to place the pinions in mesh with the adding racks 130. This the spring is free to do when the total is a positive amount, thus automatically conditioning the counter or totalizer for the taking of a positive total. When, however, there is a credit or negative total (or overdraft) in the totalizer and said total or overdraft is to be printed, it is necessary that the 10 totalizer pinions be prevented from moving into mesh with the adding racks 130 at the conclusion of the blank or spacing cycle. This result could be effected by holding the subtraction key depressed during the spacing cycle. Inasmuch, 15 however, as the operator may not know that the total is negative, means is provided for automatically maintaining the computing mechanism in condition for the printing of a negative total, if the cycle last preceding the blank cycle 20 was a subtraction cycle, or for placing the counter in operative relation to the subtraction racks 129 if the cycle last preceding the blank cycle was an adding cycle. Said means comprises a 25 forwardly extending arm 1072 (Fig. 4) pivoted in the machine frame at 1073 and underlying a stud 1074 on the member 1057. Rigid with the arm 1072 is a downwardly extending arm 1075 to which the rear end of a link 1076 is pivoted at 1077. To the forward end of the link 1076 30 is attached a contractile spring 1078 which tends to pull the link forward and thus raise the arm 1072 and hence the member 1057 so as to place the computing mechanism in position for the printing of a negative total. When an amount 35 is set up by depression of one or more keys 49, the spring 1078 is prevented from drawing the link 1076 forward by means of a stop finger 1079 (Fig. 9) fixed to the right-hand end of the rock shaft 233 (see Fig. 8) inasmuch as the 40 spring 235 turns said shaft so as to raise the stop finger 1079 into the path of a lug 1080 on the link 1076. When no amount is set up in the key board (as is the case when a spacing cycle 45 is to be performed preparatory to the printing of a total), the roller stud 236 holds the stop finger 1079 down out of the path of the lug 1080, the spring 1078 being then restrained by reason of the fact that a roller stud 1081 (Fig. 8) mounted on the axis 23a (Fig. 1) normally lies 50 in front of a lug 1082 (Fig. 11) on the arm 1075. The normal position just referred to is shown in Figs. 1 and 8, where it will be seen that the handle 27 is in initial position. When the handle is drawn forward to effect printing of the 55 total, the roller stud 1081 moves forward, thus allowing the spring 1078 (Fig. 4) to draw the link 1076 forward and thus lift the arm 1072 and the member 1057 whereby the computing mechanism is placed or maintained in position 60 to print a negative total.

It will be seen that the keyboard controls the means (1079, etc.) which controls the spring 1078 that tends to place the link 240 in position to condition the computing or registering mechanism for the taking of a negative total.

When the totalizer contains a positive total, the spring 1078 must be prevented from acting, this result being automatically effected by the means to be now described.

A stop arm 1083 (Fig. 8) pivoted in the machine frame at 1084 has a shoulder 1085 that lies in front of a lug 1086 on the arm 1075, and thus restrains the spring 1078, when said stop arm is in its upper position. The position of the stop 75

arm depends upon the nature of the total accumulated in the totalizer, said arm being in its upper position when there is a positive total in the totalizer, and being in its lower or ineffective position when the total is negative.

Referring now to Figs. 14, 14a, 15 and 15a: Motion is transmitted from the members 218^a to the stop arm 1083 by means of a link 1087 having elongated openings 1088 to receive headed studs 1089 on the members 218^a. The rear end of the link 1087 is pivotally connected to an arm 1090 which is pivoted at 1091 in the machine frame. Rigid with the arm 1090 is an arm 1092 to which is fixed a bar 1093 that is pivoted to the rear end of the stop arm 1083 (see Fig. 11). The stop arm 1083 is yieldingly held in adjusted position by means of a latch 1094 (Fig. 14) which is pivoted at 1095 in the machine frame and which has two notches 1096 in either of which the upper edge of the arm 1090 is adapted to lie. A contractile spring 1097 keeps the latch 1094 pressed against the arm 1090.

When the forward pawl 218^a is tripped to introduce a unit into the totalizer at the time the latter passes from the positive to the negative condition, the link 1087 is pushed rearwardly, (the stud and slot connection preventing interference with the rear pawl 218^a), thereby lowering the stop arm 1083 and thus leaving the spring 1078 free to function at the proper time in the cycle. If addition subsequently occurs and the totalizer passes from the negative to the positive condition, the rear pawl 218^a will be tripped to introduce a unit, thereby pushing the link 1087 forward and thus raising the stop arm 1083 into position to restrain the spring 1078.

It will be evident that the stop arm 1083, which prevents the spring 1078 from acting when a positive total is to be taken, is controlled solely by the counter or registering mechanism, the position of said arm being dependent solely upon the positive or negative character of the total contained in the registering mechanism, and being entirely independent of the paper carriage.

Summarizing the operation of taking a total, it will be observed that the main operating mechanism, acting through the link 141 (Fig. 1) conditions the counter or registering mechanism for the taking of totals; that the spring 231 (Fig. 1) acting through the link 240, tends to position the lever 219 so that the main operating mechanism shall condition the counter for the taking of a positive total; that the spring 1078 (Fig. 4) acting through the link 1076, the bell crank 1075—1072, the member 1057, and the link 240 (Fig. 7), tends to position the lever 219 so that the main operating mechanism shall condition the counter for the taking of a negative total; that said springs 231 and 1078 are wholly independent of the paper carriage, thus rendering possible the use in a machine having no laterally movable paper carriage of means for automatically conditioning the counter for the taking of totals of the correct sign; that the stop arm 1079 (Fig. 4) which prevents the spring 1078 from acting when a total is not to be taken, is sensitive to the condition of the keyboard; and that the stop arm 1083 which restrains the spring 1078 when a positive total is to be taken, is sensitive to the character of the total contained in the counter.

The initial or normal position of the arm 1079, whether an item-entering or a total-taking cycle is to be performed, is the withdrawn or ineffective position. Upon the setting up of a digit the

arm 1079 moves out of its initial position into its effective position.

It will be noted that the means for automatically conditioning the counter for the taking of totals of correct sign includes the actuating springs 231 and 1078 and the main operating mechanism, and that said springs act during the same cycle in which the main operating mechanism acts, hence making possible, during a single blank or spacing cycle, the automatic conditioning of the counter for the taking of a total of the correct sign; whereas in a certain other machine one cycle is required during which the main operating mechanism positions a certain member and another cycle is required to enable the main operating mechanism to actuate said member to condition the registering mechanism for the taking of a negative total in still another cycle.

After taking a negative total from the machine herein disclosed, adding can be done immediately and the correct result obtained, because the fugitive unit is introduced in connection with the addition of the first item following the taking of a negative total.

In the present machine, the counter always represents the correct total at the end of any accumulating cycle (whether additive or subtractive), because the fugitive unit is introduced only when the counter passes through zero; whereas in machines of the type shown in the Rinsche Patent No. 1,172,484 the registering mechanism does not always represent the correct total at the end of an accumulating cycle, for the reason that the fugitive unit is introduced whenever the registering mechanism is moved into mesh with the racks after a shift from addition condition to subtraction condition or vice versa, the fugitive unit thus being sometimes needlessly introduced, as when a smaller number is subtracted from a larger positive amount.

The means for turning the platen sections 2^a and 2^b may be of any preferred construction. Herein each platen section has connected to its outer end a ratchet wheel 1098 (Fig. 20) arranged to be engaged by a dog 1099. The dogs 1099 are pivoted upon the ends of a rod 1100 which is suspended from the framework of the carriage 1 by means of links 1101. The means for imparting a feed stroke to the dogs 1099 comprises a slide 1102 (Fig. 17) guided in the machine frame for horizontal reciprocation longitudinally of the machine. Said slide has a notch 1103 through which the rod 1100 is slidable as the paper carriage moves laterally. On the left-hand lever 19 is a stud 1104 adapted to engage a shoulder 1105 on the slide 1102 to move said slide in the direction to retract the dogs 1099. A contractile spring 1106 serves to move the slide in the opposite direction.

The means for automatically controlling the line-space or platen-turning mechanism comprises a stop plate 1107 (Figs. 16, 17 and 18a) mounted on the stationary track 1108 of the carriage 1 for movement in a direction parallel with the direction of travel of the carriage. 1109 are elongated openings in said stop plate through which extend screws 1110 seated in the track 1108. On the left-hand end of the stop plate 1107 is a detent portion 1111 which is normally held in the path of the slide 1102 through the action of a contractile spring 1112. On the opposite end of the stop plate 1107 is a lug 1113 which lies behind a slide 1114 (Fig. 22). Said slide has a lug 1115 adapted to be engaged by one or more stop pins 1116 (Fig. 30) on the stop

plate 1010. The spring 1112 normally holds the slide 1114 away from the abutment 1006. When a stop pin 1116 on the carriage 1 pushes the slide 1114 against the abutment, the detent portion 1111 is moved out of the path of the slide 1102, thereby permitting the latter to impart one feed stroke to the dogs 1099.

When the machine is to be used for ordinary listing, it is desirable that means be provided for 10 manually setting the stop plate 1107 in position to allow line spacing. Herein is shown a slide 1117 (Figs. 16 and 34) mounted on the track 1108 by means of a screw 1118 extending through a slot 1119 in said slide. On one end of the 15 slide 1117 is a handle 1120. The other end of the slide is connected to the stop plate 1107 by means of a pin 1121 on the stop plate extending into an elongated opening 1122 in the slide. The 20 length of the slot 1119 is such that when the slide 1117 is moved to the left (Fig. 34) as far as it will go, the stop plate 1107 is shifted into position to permit actuation of the line-space mechanism. Friction holds the slide 1117 in adjusted 25 position.

25 Referring now to the mechanism for releasing the spring-actuated printing hammers (not shown): Said mechanism comprises a lever 1123 (Fig. 10) which is pivoted at 1124 to a hammer-release lever 1125 that is pivoted at 1126. In 30 the lower edge of the lever 1123 is a notch 1127. On the inner side of the arm 25 is a stud 1128. When the handle 27 is pulled forward, the arm 25 swings up, the stud 1128 lifting the lever 1123 slightly and passing into the notch 1127. When 35 the handle starts to return, the arm 25 causes the levers 1123 and 1125 to turn as a unit on the axis 1126, thereby releasing the hammers.

The non-print means for automatically preventing release of the hammers comprises a 40 lever 1129 pivoted at 1130. The forward end of said lever underlies a stud 1131 on the lever 1123. A contractile spring 1132 tends to move the lever 1129 to raise the lever 1123 above the path of movement of the stud 1128, thus preventing 45 said stud from moving the levers 1123 and 1125. Normally the lever 1129 is prevented from moving under the influence of the spring 1132 by means of a lug 1133 (Fig. 18a) on the stop plate 1107, said lever having a lug 1134 adapted to overlie the lug 1133. One or more 50 stop pins 1135 (Fig. 30) are provided on the stop plate 1010 in line with the lug 1115, but offset to the right with respect to the position of rest of the carriage so as to impart only 55 a partial movement to the slide 1114. There is a slot 1136 in the stop portion 1111 through which the lug 1134 may pass down under the action of the spring 1132 when the stop plate 1107 is moved by reason of the impingement of a stop pin 1135 upon the lug 1115. The rear 60 end 1137 (Fig. 10) of the lever 1129 bears against a roller stud 1138 on the left-hand lever 19. When the stop plate 1107 is shifted by a stop pin 1135 and the handle 27 is pulled forward, the lever 1129 follows the stud 1138, the lug 1134 descending through the slot 1136, and the forward end of the lever 1129 raising the lever 1123 into inoperative position, thereby preventing 65 printing. When the handle returns, the lever 19 swings the lever 1129 back to normal position, with the lug 1134 above the lug 1133.

Movement of the stop plate 1107 through the medium of a stop pin 1116 places a shoulder 1139 on said stop plate under the lug 1134, and thus

75 prevents the lever 1129 from disabling the printing mechanism.

For each position in which it is desired that the carriage halt, there is provided on the stop plate 1010 a stop pin 1140 (Fig. 30) adapted to engage a stop lug 1141 (Fig. 25) fixed adjacent to the abutment 1006. In order to disengage the pin 1140 from the lug 1141 when the carriage is to be moved to the next position, I place on the stop plate adjacent to each pin 1140 10 except the one farthest to the right an escapement or spacing pin 1142 adapted to engage an escapement dog 1143 (Figs. 1, 1a, and 26), which is guided for approximately vertical reciprocation alongside the stop lug 1141. When the escapement dog is in normal or upper position it is in position to be pressed against the abutment 1006 by a pin 1142. The dog 1143 is pivoted at 1144 to a lever 1145 which is pivoted at 1146 in the machine frame. A contractile spring 1147 tends 20 to swing the lever 1145 downwardly to withdraw the dog 1143 from the pin 1142. The lever 1145 is normally held up by a roller stud 1148 on the right-hand lever 19. A contractile spring 1149 (Fig. 26) tends to move the dog 1143 to the 25 right, i. e., away from the abutment 1006, and against a stop 1150. When the handle 27 is pulled forward the lever 19 turns in the direction to lower the roller stud 1148, whereupon gravity and the spring 1147 lower the lever 1145 and 30 the escapement dog 1143. As soon as the dog 1143 is below the pin 1142, the spring 1149 moves the dog into position below said pin. In the return stroke of the handle, the roller stud 1148 lifts the lever 1145, the dog 1143 lifting the pin 35 1142 until the adjacent pin 1140 is above the stop lug 1141, whereupon the spring 1000 (Fig. 16) moves the carriage to the left until the next pair of pins 1140 and 1142 stop against the lug 1141 and the dog 1143, respectively. The various positions at which the carriage stops are indicated in Fig. 30 by numerals enclosed in circles.

In order to permit of moving the carriage 1 from one position to the next without operating the handle 27, I provide means including a tabulating key 1151 (Fig. 1) carried by a lever 1152 which is pivoted at 1039 in the machine frame. To one arm of the lever 1152 is pivoted a link 1154 which in turn is pivoted to one arm of a lever 1155 (Fig. 1b) mounted to swing on the axis 1146. To the other arm of the lever 1155 is pivoted a tabulator dog 1156 which is guided for up and down movement alongside the dog 1143. A contractile spring 1157 (Fig. 27) normally holds the dog 1156 away from the abutment 1006 and against a stop 1158. 1159 (Fig. 1) is a contractile spring which normally holds the tabulator key 1151 elevated and the tabulator dog 1156 in its lower position. At desired 60 points on the stop plate 1010 are tabulating pins 1160 (Fig. 30) which stand above the tabulator dog 1156 when the carriage is halted by engagement of a stop pin 1140 with the lug 1141. It will be seen that by depressing the tabulator key 65 1151, the operator may raise the tabulator dog 1156, thereby lifting the pin 1160, and thus, raising the stop plate 1010 until the pin 1140 is above the lug 1141, whereupon the carriage moves to the left until arrested by engagement of a 70 pin 1140 with the lug 1141.

At those carriage positions where a blank or spacing stroke of the handle should occur preparatory to printing a total in the next column, no tabulating pin 1160 is provided on the stop 75

plate 1010, thus compelling the use of the handle in effecting movement of the carriage to the position where a total should be printed.

To illustrate the capabilities of the machine, I have shown it as equipped with a split platen and with a stop plate designed to control the machine for the preparation of a statement and for posting to a ledger sheet. It will be understood, however, that the invention is applicable to a machine having a unitary platen, and that the machine is adapted to do bank bookkeeping as well as commercial bookkeeping.

Referring now to Fig. 30: It may be stated that it is common practice to make entries upon the monthly statement A at the same time that corresponding entries are made upon the ledger sheet B. In machine bookkeeping it is usual first to post all debits to the various accounts and then post all credits. Assuming that the operator is about to commence posting a number of debits, the following operations are performed.

(1) A debit posting stop plate 1010 is attached to the paper carriage 1.

(2) The totalizer is cleared by manually depressing the clear key 169 and operating the handle 21.

(3) The dating buttons 511 (Fig. 17) are slid to appropriate positions. In the example shown in Fig. 30, the left-hand button 511 is slid into position opposite the abbreviation "Aug." and the right-hand button 511 is slid into position opposite the numeral 2.

(4) The statement blank is inserted in the carriage at the left-hand side of the plane of division of the platen, and the ledger sheet at the right-hand side of said plane of division.

(5) The lines on which printing is to be done on the two sheets are brought into alignment with each other by manually rotating the platen sections, and the sheets are placed in proper columnar printing position by manually adjusting the sheets to the right or left.

(6) The carriage is brought to its extreme right-hand position (position No. 1 in Fig. 30) wherein the Date and Charges columns on the statement are behind the type bars. The first stop pin 1140 on the stop plate 1010 then stands against the lug 1141, and the escapement dog 1143 bears against the first pin 1142 on said stop plate. The first stop pin 1009 on the stop plate is in contact with the lug 1008 (Figs. 28 and 34), whereby the detent lugs 1002 are held out of engagement with the date type bars. The first stop pin 1030 on the stop plate stands against the lug 1029^a (Fig. 29), whereby the pin 1025 is held in the path of the bar 74 (Fig. 10). The first non-add stop pin 1048 on the stop plate bears against the lug 1046 (Fig. 24), whereby the stop 1052 (Fig. 3) is held out of the path of the arm 1051.

(7) The amount of the debit item to be posted to the customer's account being \$18.75, the operator sets up this amount on the keyboard of the machine and pulls the handle 21. The date and the debit item are thereby printed upon the statement without being added. As the handle returns the roller stud 1148 (Fig. 1a) lifts the lever 1145, thus pushing the escapement dog 1143 against the pin 1142, whereby said pin 1142 is lifted until the adjacent pin 1140 is above the stop lug 1141, whereupon the spring 1000 moves the carriage to the left until the next pair of pins 1140 and 1142 stop against the lug 1141 and the dog 1143, respectively. The Date column and the Charges column on the ledger sheet are then

behind the type bars. As the carriage comes to rest in such position, the second stop pin 1009 on the stop plate engages the lug 1008 (Figs. 28 and 34) whereby the detent lugs 1002 are moved out of engagement with the date-printing type bars.

(8) The operator again pulls the handle 21, whereby the debit 18.75 and the date thereof are printed in the proper columns on the ledger sheet, and the amount of the debit is added. In the return movement of the handle, the carriage automatically moves to position the folio column behind the type bars. As the carriage comes to rest in such position, the first stop pin 1048 on the stop plate 1010 engages the lug 1046 (Fig. 15 24), whereby the link 1035 (Fig. 12) is moved laterally into position to be engaged by the pin 1040.

(9) The operator then sets up the folio 1842 on the keyboard and pulls the handle. As the handle is pulled forward, the link 1035 is pushed forward so that as the handle returns the adding wheels are prevented from going into mesh with the racks 130, thus preventing the folio from being added. As the handle returns to initial 25 position, the carriage moves to the "blank" position indicated by the number 4 in Fig. 30. As the carriage comes to rest in such position, the first non-print stop pin 1135 (Fig. 30) on the stop plate 1010 engages the lug 1115 (Fig. 22), 30 whereby the stop plate 1107 (Fig. 18a) is moved into position to allow the lug 1134 to move down through the slot.

(10) The operator sets up on the keyboard the "old balance" of 125.00 and pulls the handle, 35 whereby the old balance is added to the debit of 18.75 just posted, but is not printed. As the handle returns, the carriage moves to Position 5, wherein the second non-print stop pin 1135 (Fig. 30) comes into action.

(11) The operator pulls the handle twice, the first being a blank stroke which causes the carriage to move to Position 6, (wherein the second stop pin 1030 on the stop plate 1010 bears against the lug 1029^a, whereby the stop 1052 is moved 45 to the left out of the path of the arm 1051); and the second actuation of the handle causing the total (143.75) of the old balance and the new debit to be printed in the balance column. As the handle returns the second time the carriage 50 moves to Position 7. As the carriage reaches said position the stop pin 1071 (Fig. 21) on the stop plate 1010 engages the lug 1070, whereby the lever arm 1062 is raised into position in front of the lug 1061.

(12) The operator now sets up the "old balance" 125.00 on the keyboard and pulls the handle, whereby the old balance is printed in the column headed "Second pick-up of old balance" and is subtracted from the amount in the totalizer. As the handle returns the carriage moves to the blank position indicated at 8 in Fig. 30.

(13) The operator pulls the handle twice, the first being a blank stroke which causes the carriage to move to Position 9, in which position the third stop pin 1030 on the stop plate acts to hold the stop 1052 out of the path of the arm 1051, and the second stop pin 1048 bears against the lug 1046 and the stop pin 1116 stands against the lug 1115 (Fig. 22). As the handle returns the second time, the remainder 18.75 is printed in the "proof of posting" column, the totalizer is cleared and the platen sections 2^a and 2^b are rotated one line space. By comparing the amount printed in the "proof of posting" column with that printed 75

in the charge column on the statement, the operator may ascertain whether error has occurred in the work done on the ledger sheet.

(14) The statement and ledger sheet are then replaced by the statement and ledger sheet of the next customer against whom there is a charge to be made.

(15) When all the debits have been posted, it is preferable to prove the correctness of the work by inserting a roll of tape in the machine, and adding and listing the last amount appearing in the "Proof of posting" column on all the ledger sheets to which posting has been done. The total of these amounts should agree with the predetermined total made of the debit items before posting began.

The credits are posted in substantially the same way as just described in connection with debits, a credit posting stop plate generally similar to the plate 1010 being used in order to cause the carriage to stop with the proper columns in operative relation to the type bars and in order to cause the paper carriage to control the various adding machine mechanisms as required to effect repeated printing of the date, subtraction of credits, non-addition of the folio, non-printing of old balance, clearing of the machine, and platen feed.

Any preferred means may be employed to effect printing of required signals, such as non-add, subtraction, credit balance, subtotal or clear. To prevent the printing of a minus or credit signal at position 5 (Fig. 30) on the spacing stroke, the second non-print stop pin 1135 is provided.

While the present embodiment of the invention has been described in considerable detail, it will be understood that the several mechanisms may be modified in various respects and certain mechanisms omitted, if desired, without departing from the spirit and scope of the invention as set forth in the appended claims.

I claim as my invention:

1. The combination of computing mechanism, mechanisms for printing the items and the computations, a laterally movable paper carriage, a carriage escapement stop, a carriage escapement dog, a plurality of members controlling said computing and printing mechanisms, a stop plate pivoted to and detachably connected with the paper carriage, and stop pins permanently secured to said plate adapted to engage said escapement stop, escapement dog and members in the movement of the paper carriage.

2. A computing and printing machine having date-printing mechanism including type carriers and pivoted arms for actuating said type carriers, a slide having lugs thereon arranged to obstruct movement of said arms, a spring normally holding said slide in effective position, a laterally movable paper carriage, and means actuated by said carriage for moving said slide out of effective position.

3. A computing and printing machine having date-printing mechanism including type carriers and pivoted arms for actuating said type carriers, a member arranged to obstruct movement of said arms, a spring normally holding said member in effective position, a laterally movable paper carriage, and means actuated by said carriage for moving said member out of effective position.

4. A computing machine having, in combination, adding mechanism comprising a reversible pawl, non-add mechanism comprising a part for

holding the pawl in ineffective position and a laterally movable paper carriage, and means under the control of said carriage for actuating said part, said means including a member movable to and fro in every operation of the machine, 5 a second member adapted to be engaged by the first member, a third member which normally holds the second member out of position for engagement by the first member, and means actuated by the carriage for moving the third member 10 to move the second member laterally into position for engagement by the first member.

5. In a computing machine having a laterally movable paper carriage, controlling mechanism comprising a rock shaft on the carriage having 15 a flat side, a pivot pin, a locking pin and a spring-pressed headed stud on the flat side of said rock shaft, a stop plate having apertures to receive the pivot pin and the locking pin and a notch in one edge to receive said stud, and a plurality of 20 stop pins permanently secured to said plate.

6. The combination of computing mechanism, mechanisms for printing the items and the computations, a laterally movable paper carriage, a carriage escapement stop, a carriage escapement 25 dog, a plurality of members controlling said computing and printing mechanisms, a stop plate pivoted to the paper carriage and arranged to overlie said stop, dog and members, and stop pins 30 permanently secured to the underside of said plate adapted to engage said stop, dog and members in the movement of the paper carriage.

7. The combination of printing mechanism, a laterally movable paper carriage, a carriage escapement stop, a carriage escapement dog, a 35 plurality of members controlling said printing mechanism, a stop plate pivoted to the paper carriage and arranged to overlie said stop, dog and members, and stop pins permanently secured to the underside of said plate adapted to 40 engage said stop, dog and members in the movement of the paper carriage.

8. The combination of computing mechanism, a laterally movable paper carriage, carriage escapement means, a plurality of members controlling said computing mechanism, a stop plate pivoted to the paper carriage and arranged to overlie said escapement means and members, and stop pins permanently secured to the underside of said plate adapted to engage said escapement 50 means and members in the movement of the paper carriage.

9. The combination of computing mechanism, mechanisms for printing the items and the computations, a laterally movable paper carriage, carriage escapement devices, a plurality of members controlling said computing and printing mechanisms, said devices and members being compactly grouped together, a stop plate pivoted to the paper carriage and arranged to overlie said devices and members, and stop pins arranged in rows on the underside of said plate in position to engage said devices and members in the movement of the paper carriage.

10. A computing machine having, in combination, non-print mechanism including a pivoted lever, a spring tending to move said lever into effective position, means normally preventing such movement of said lever, a laterally movable paper carriage, and means actuated by the carriage for moving said preventing means into ineffective position.

11. Computing mechanism comprising two sets of racks facing each other, a single set of recipro-

- catory members to which both sets of racks are connected, a set of pinions located between the two sets of racks and arranged to mesh with either set, a set of transfer devices for each set of racks, 5 means for moving the units rack of each set of racks to introduce the fugitive unit, means actuated by the pinion of highest order for actuating said means for introducing the fugitive unit, means tending to set the computing mechanism during one cycle for engagement of the pinions with a certain set of racks during the next cycle, and means actuated in the operation of the fugitive-unit-introducing means for controlling said setting means. 10
- 15 12. The combination of computing mechanism arranged for addition and direct subtraction, means for introducing the fugitive unit, means tending to set the computing mechanism during one cycle to perform a negative-total operation in another cycle, and means actuated in the operation of the fugitive-unit-introducing means for controlling said setting means.
- 20 13. Direct subtraction mechanism comprising a set of adding racks and a set of subtracting racks, a set of pinions arranged to mesh with either set, two sets of transfer devices one for each set of racks, means for moving the units subtracting rack to introduce the fugitive unit into the set of pinions, means for moving the units adding rack to introduce the fugitive unit into the set of pinions, and means actuated by the pinion of highest order for actuating said means for introducing the fugitive unit. 25
- 25 14. Computing mechanism comprising two sets of racks facing each other, a single set of reciprocatory members to which both sets of racks are connected, a set of pinions located between the two sets of racks and arranged to mesh with either set, a set of transfer devices for each set of racks, 30 means for moving the units rack of each set of racks to introduce the fugitive unit into the set of pinions, and means actuated by the pinion of highest order for actuating said means for introducing the fugitive unit.
- 35 15. Computing mechanism comprising two sets of racks, a single set of reciprocatory members to which both sets of racks are connected, a set of pinions arranged to be rotated in opposite directions by said sets of racks, means for moving the units racks to introduce the fugitive unit, two pivoted pawls each for restraining one of the units racks, two diametrically opposite lugs connected to revolve with the pinion of highest order, two spring-actuated members each arranged to be tripped by one of said lugs, and two pivoted members each rigidly connected to one of said pawls, each of said spring-actuated members being attached to one of said pivoted members. 40
- 40 16. Computing mechanism comprising two sets of racks, a set of pinions arranged to be rotated in opposite directions by said sets of racks, means tending to move the units rack of each set to introduce the fugitive unit, two pawls each for restraining one of the units racks, transfer devices for the remaining racks, means connected to revolve with the pinion of highest order, and means arranged to be actuated by said revolving means to move said pawls out of units-rack-restraining position. 45
- 45 17. Computing mechanism comprising two sets of racks facing each other, a single set of reciprocatory members to which both sets of racks are connected, a set of pinions located between the two sets of racks and arranged to mesh with either set, each pinion having twenty teeth and two 50
- diametrically opposite transfer lugs, two sets of transfer devices, one for each set of racks, means for moving the units racks to introduce the fugitive unit, and means actuated by the pinion of highest order for controlling said units-rack-moving means. 5
- 55 18. Computing mechanism comprising two sets of racks facing each other, a single set of reciprocatory members to which both sets of racks are connected, a set of pinions located between the two sets of racks and arranged to mesh with either set, means for moving the units rack of each set to introduce the fugitive unit, two pawls each for restraining one of the units racks, two diametrically opposite lugs connected to revolve with the pinion of highest order, and means actuated by said lugs for withdrawing said pawls from rack-restraining position. 10
- 60 19. Computing mechanism comprising a set of racks, a set of pinions arranged to mesh with the racks, a spring tending to move the units rack to introduce the fugitive unit, a pawl to restrain the units rack, transfer devices for the remaining racks, a lug connected to revolve with the pinion of highest order, means arranged to be engaged by said lug and connected to said pawl to move the latter out of units-rack-restraining position, another set of racks facing the first mentioned set of racks and arranged to mesh with said pinions, means for moving the units rack of the second set to introduce the fugitive unit, transfer devices for the remaining racks of the second set, and means actuated by the pinion of highest order for controlling the last mentioned fugitive-unit-introducing means. 15
- 65 20. Computing mechanism comprising a set of racks, a set of pinions arranged to be rotated by the racks, a spring tending to move the units rack to introduce the fugitive unit, a pawl to restrain the units rack, transfer devices for the remaining racks, a lug connected to revolve with the pinion of highest order, means arranged to be engaged by said lug and connected to said pawl to move the latter out of units-rack-restraining position, another set of racks arranged to rotate said pinions, means for moving the units rack of the second set to introduce the fugitive unit, and means actuated by the pinion of highest order for controlling the last mentioned fugitive-unit-introducing means. 20
- 70 21. Computing mechanism comprising a set of racks, a set of pinions arranged to be rotated by the racks, a spring tending to move the units rack to introduce the fugitive unit, a pawl to restrain the units rack, a spring tending to withdraw the pawl, transfer devices for the remaining racks, a lug connected to revolve with the pinion of highest order, a member rigidly connected to the pawl, and a part connected to said member and normally restraining the second mentioned spring and arranged to be moved by said lug to allow the second mentioned spring to move the pawl out of units-rack-restraining position. 25
- 75 22. A totalizer comprising a set of pinions arranged to be rotated in one direction to add and in the opposite direction to subtract, means to introduce the fugitive unit into said set of pinions whenever the totalizer passes through zero, means to set the totalizer to perform a negative operation, and means actuated in the operation of the fugitive-unit-introducing means for controlling said setting means. 30
- 80 23. Computing mechanism comprising two sets of racks, a set of pinions arranged to be rotated in opposite directions by said sets of racks, 35

- means tending to move the units rack of each set to introduce the fugitive unit, two pawls each for restraining one of the units racks, transfer devices for the remaining racks, means connected 5 to revolve with the pinion of highest order, means arranged to be actuated by said revolving means to move said pawls out of units-rack-restraining position, means to set the computing mechanism to perform subtraction, and means actuated in 10 the operation of the fugitive-unit-introducing means for controlling said setting means.
24. A cross-tabulating adding machine having, in combination, a supporting framework, computing and printing mechanism, a laterally 15 movable paper carriage mounted on top of the framework, a carriage escapement stop, a carriage escapement dog, a plurality of members controlling said computing and printing mechanism, said stop, dog and members being com- 20 pactly grouped together one behind another and located adjacent to the carriage, a stop plate pivoted at its forward edge to the rear portion of the carriage and overlying said group of controlling members, stop and dog, and stop ele- 25 ments on the lower side of said plate to coact with the elements of said group.
25. The combination with computing mechanism arranged for addition and direct subtraction and comprising a set of adding racks, a set 30 of subtracting racks, a set of pinions movable into mesh with either set of racks and means for introducing the fugitive unit into said set of pinions whenever the set of pinions passes through zero, of means for automatically moving the set of pinions into mesh with the subtracting racks when 35 there is a negative total in the set of pinions.
26. The combination in a calculating machine of depressible keys, two series of actuators controlled by the keys and arranged in denomina- 40 tional orders, a series of registering elements having a positive zero position and a negative zero position, said registering elements being identified with the two series of actuators and operable optionally thereby to accumulate numbers 45 either additively or subtractively and to represent the true algebraic sum thereof notwithstanding the said sum may alternately be of a positive or negative character, automatic means whereby the actuators in lowest denominational 50 order will be caused to move the identified registering element a distance corresponding to one unit as an incident to a change in the character of the sum represented by said registering elements, clearing means whereby said elements 55 may be set in either of their zero positions, recording means operable to print the sum represented by the registering elements as an incident to the setting of said elements in zero position, and means responsive to the positive or negative 60 character of the sum represented by the registering elements for automatically conditioning the machine for a subtraction type of engagement between said actuators and registering elements when there is a negative sum in said elements. 65
27. In a bookkeeping machine, a paper carriage having an elongated control plate, a pivot member to which said plate is detachably connected, and means for thus securing the plate to said pivot member comprising a series of 70 spring-actuated headed studs on said pivot member, said plate having along one of its long edges a series of openings for the reception of said studs, and means for detachably holding the plate in association with said studs.
28. In a bookkeeping machine, a paper car- 75
- riage having an elongated control plate, a pivot member to which said plate is detachably connected, and means for thus securing the plate to said pivot member comprising a series of spring-actuated headed studs on said pivot member, said plate having along one of its long edges a series of openings for the reception of said studs, and pin-and-hole connections between the end portions of said plate and said pivot member. 5
29. A computing and printing machine having, in combination, a main operating mechanism, a registering mechanism adapted to be conditioned for addition or subtraction, total taking means for taking either a negative or a positive total from said registering mechanism, means for introducing the fugitive unit into the registering mechanism in item-entering operations, and means effective in a single blank cycle of operation of said operating mechanism for automatically 10 conditioning the registering mechanism for the taking of a total of the correct sign.
30. A computing and printing machine having, in combination, a main operating mechanism, a registering mechanism adapted to be conditioned for addition or subtraction, said registering mechanism comprising pinions, and spring-actuated means controlled by the registering mechanism when an over-draft occurs therein for conditioning the machine to cause 15 operation of the operating mechanism to automatically condition the registering mechanism in one blank cycle of operation of the machine without rotation of the pinions, for the taking of a true negative total therefrom in a single 20 subsequent cycle of operations, said spring-actuated means being effective in the same cycle in which the operating mechanism thus conditions 25 the registering mechanism. 30
31. A computing and printing machine having, in combination, a main operating mechanism, a registering mechanism adapted to be conditioned for addition or subtraction, said registering mechanism comprising pinions, total-taking means for taking either a negative or a positive total from said registering mechanism, and means for causing operation of the operating mechanism during a blank cycle thereof to automatically condition the registering mechanism without rotation of the pinions, for the taking of a total of the sign corresponding to 40 the sign of the total in said registering mechanism, said last-mentioned means being governed by said registering mechanism in response to the negative or positive character of the total therein 45 in the same cycle in which the operating mechanism effects said conditioning. 5
32. A computing machine having, in combination, a keyboard, a registering mechanism adapted to be conditioned for addition or subtraction or total-taking, mechanism tending to effect conditioning of said mechanism for a negative total-taking operation, and means controlled by the keyboard for controlling the second-mentioned mechanism. 6
33. A computing machine having, in combination, a keyboard, a main operating mechanism, a registering mechanism, means actuated by the main operating mechanism for conditioning the registering mechanism for positive or negative total-taking operation, spring-actuated means for conditioning the first-mentioned means to effect conditioning of the registering mechanism for a negative total-taking operation, and means controlled by the keyboard for disabling the spring-actuated means. 6

34. A computing and printing machine having, in combination, a keyboard, a registering mechanism adapted for addition, direct subtraction, and positive and negative total-taking, means for 5 conditioning the registering mechanism for a negative or a positive total-taking operation, said means including a spring tending to effect conditioning for a negative total-taking operation, and means controlled by the keyboard for restraining the spring.
35. A computing machine having a counter comprising a series of pinions, pinion-rotating means comprising two sets of racks, one set for rotating the pinions in one direction to add and the other set for rotating the pinions in the opposite direction to subtract, each rack being independently movable with respect to all the others for transfer purposes, total-taking means including said pinion-rotating means for taking a 10 total from the pinions through rotation of the pinions to a zero position, and means controlled by the pinion of highest order for causing said pinion-rotating means to introduce a unit into the units pinion whenever the pinion of highest order passes through zero in either direction and prior to the operation of the total-taking means.
36. A computing machine having a counter comprising a series of pinions, means for rotating the pinions in one direction to add and in the opposite direction to subtract, total-taking means including said pinion-rotating means for taking a total from the pinions through rotation of the pinions to zero, means controlled by the pinion of highest order for causing said pinion-rotating 15 means to introduce a unit into the units pinion whenever the pinion of highest order passes through zero in either direction and prior to the operation of the total-taking means, a device which is controlled by the counter and which occupies one position when the counter contains a positive total and another position when the counter contains a negative total, and means tending to set the machine for a negative total-taking operation, said last-mentioned means being restrained by said device when the latter is in positive position.
37. A computing machine comprising a series of pinions each having twenty teeth and two diametrically opposite lugs, means for rotating the pinions in one direction to add and in the opposite direction to subtract, two sets of transfer devices, one to effect transfers in addition and the other to effect transfers in subtraction, the lugs of the pinions below the highest order being arranged to operate said devices, and means controlled by the lugs of the pinion of highest order for causing the pinion-rotating means to turn the units pinion one tooth-space whenever the pinion of highest order passes through zero in either direction.
38. A computing machine comprising a series of pinions each having twenty teeth and two diametrically opposite lugs, means for rotating the pinions in one direction to add and in the opposite direction to subtract, two sets of transfer devices, one to effect transfers in addition and the other to effect transfers in subtraction, the lugs of the pinions below the highest order being arranged to operate said devices, and two mechanisms controlled by the lugs of the pinion of highest order for causing the pinion-rotating means to turn the units pinion one tooth-space whenever the pinion of highest order passes through zero, one of said mechanisms operating when the last-mentioned pinion passes through zero in one direction and the other mechanism operating when said pinion passes through zero in the opposite direction.
39. In a machine of the class described, racks of different denominational orders, a registering mechanism capable of addition or subtraction, said registering mechanism having pinions of orders corresponding to said racks and adapted to engage said racks, a printing mechanism controllable by said registering mechanism for printing the exact amounts in said registering mechanism, means for automatically actuating the units rack to introduce the fugitive unit into said registering mechanism in item-entering operations in order to place the same in correct condition when the registering mechanism changes from positive to negative condition and vice versa immediately upon and as an incident to a change in the character of the total in the registering mechanism, a total-taking means for conditioning said machine to take and print from said registering mechanism the actual total contained therein, and means controlled by said registering mechanism acting automatically to condition said machine so that, when a total is taken, the true positive or the true negative total will be automatically printed in accordance with whether the total in said registering mechanism is positive or negative.
40. In a machine of the class described, racks of different denominational orders, register pinions of corresponding orders, means for causing an operating engagement between said pinions and racks in one relation for addition and in another relation for subtraction, means for introducing the fugitive unit into said pinions immediately upon and as an incident to a change in the character of the total in the registering mechanism, a total-taking means for taking from said register pinions and printing the total actually in said pinions, and means responsive to the positive or negative character of the total in said pinions for automatically conditioning the machine for a subtraction-type of engagement between the pinions and racks when there is a negative total in said pinions.
41. A computing machine having, in combination, a set of registering pinions, means for rotating the pinions in one direction to add and in the opposite direction to subtract, means to cause the fugitive unit to be automatically introduced into the set of pinions by the pinion-rotating means when the pinion of highest order is rotated through zero from positive to negative, and separate means to cause the fugitive unit to be automatically introduced into the set of pinions by the pinion-rotating means when the pinion of highest order is rotated through zero from negative to positive.
42. In a computing machine, a single set of pinions, two fugitive-unit mechanisms, one for introducing a positive unit and the other for introducing a negative unit, and means tending to condition the set of pinions for the taking of a negative total, said means being restrained by said positive-unit mechanism.
43. In a computing machine, accumulating means which tends to assume the condition for positive-total-taking, means tending to condition the accumulating means for negative-total-taking, a mechanism for introducing a negative fugitive-unit, and a mechanism for introducing a positive fugitive-unit, the last-mentioned mechanism being arranged to restrain the second-mentioned means.

44. In a computing machine, accumulating means, two fugitive-unit mechanisms, one for introducing a positive unit and the other for introducing a negative unit, and means for conditioning the accumulating means for the taking of a total of the correct sign comprising a member movable into positive-total position under the control of said positive-unit mechanism and movable into negative-total position under the control of said negative-unit mechanism.
45. In a computing machine, a registering mechanism, means for introducing a fugitive unit positively or negatively into said registering mechanism in item-entering operations as an incident to a change in the character of the total in said mechanism, and means controlled by said mechanism in accordance with the character of the total therein for automatically conditioning the registering mechanism for a negative-total operation when there is a negative total in said mechanism.
46. A bookkeeping machine having, in combination, a cross-tabulating paper carriage, a registering mechanism, means for introducing a fugitive unit into said mechanism immediately upon and as an incident to a change in the sign of the total in said mechanism, means independent of the paper carriage and controlled by said registering mechanism in accordance with the character of the total in said mechanism for automatically conditioning the machine for the taking of a total of the correct sign, and means under control of the registering mechanism for printing the total on paper held in said carriage.
47. In combination, in an accounting machine, a main operating mechanism, a registering mechanism adapted to be conditioned for addition or subtraction and for the taking of a direct negative total when the registering mechanism is in subtraction condition, and means automatically conditioned by said registering mechanism when an overdraft occurs therein for causing operation of the operating mechanism during a single blank cycle of operation to automatically place the registering mechanism in subtraction condition.
48. The combination with adding and subtracting mechanism having means for automatically introducing the fugitive unit in item-entering operations, of means controlled by the fugitive-unit means for automatically conditioning said mechanism in a single blank cycle of operation for the taking of a negative total when said mechanism contains a negative total.
49. The combination of adding and subtracting mechanism, means for automatically introducing the fugitive unit, and means controlled by the adding and subtracting mechanism in accordance with the character of the total therein for automatically conditioning said mechanism in a single blank cycle of operation for the taking of a negative total when said mechanism contains a negative total.
50. The combination of adding and subtracting mechanism, means for automatically introducing the fugitive unit in item-entering operations, and means controlled by the adding and subtracting mechanism in accordance with the character of the total therein for automatically conditioning said mechanism in a single blank cycle of operation for the taking of a negative total when said mechanism contains a negative total.
51. The combination of adding and subtracting mechanism, means for automatically introducing the fugitive unit immediately upon and as an incident to a change in the character of the total in said mechanism, and means controlled by said mechanism in accordance with the character of the total therein for automatically conditioning said mechanism for the taking of a negative total when said mechanism contains a negative total.
52. A computing machine having, in combination, numeral keys, differential mechanism, a totalizer arranged for positive or negative engagement with said differential mechanism, means tending to set the totalizer during one cycle for a negative engagement with said differential mechanism during the next cycle, and means controlled by the numeral keys for rendering said setting means ineffective when a number is set up in the keyboard.
53. In combination, in an accounting machine, a main operating mechanism, a registering mechanism adapted to be conditioned for addition or subtraction and for the taking of a direct negative total when the registering mechanism is in subtraction condition, a spring, and means automatically conditioned jointly by said registering mechanism and said spring when an overdraft occurs in said registering mechanism for causing operation of the operating mechanism in a subsequent blank cycle to automatically place the registering mechanism in subtraction condition.
54. In a machine of the class described, a register including a series of pinions, one for each denominational order, two differentially slidable racks for each of a plurality of the pinions for actuating the latter, devices for moving the said plurality of pinions each from engagement with one of its respective racks to the other of said racks, means movable by the pinion of highest order when the register overdrafts with the said plurality of pinions in one position, another means, independent of said first means, movable by the same pinion when the register overdrafts with the said plurality of pinions in the other position, total taking mechanism, and means whereby movement of either of said means controls the total taking mechanism.

OSCAR J. SUNDSTRAND. 60
